UNITED STATES PATENT OFFICE.

CARLISLE H. MIDDAUGH, OF LAWRENCEVILLE, PENNSYLVANIA.

CLASSIFYING-CABINET.

1,135,038.

Specification of Letters Patent. Patented Apr. 13, 1915.

Application filed September 27, 1912. Serial No. 722,675.

To all whom it may concern:

Be it known that I, CARLISLE H. MIDDAUGH, a citizen of the United States, residing at Lawrenceville, county of Tioga, 5 and State of Pennsylvania, have invented certain new and useful Improvements in Classifying-Cabinets, fully described and represented in the following specification and the accompanying drawings, forming a 10 part of the same.

The object of this invention is to furnish a cabinet in which mail matter and similar articles may be classified by placing them in suitable compartments or spaces, and the invention consists in the particular constructions shown and claimed herein for facilitating the separating and the holding of the matter, and the removal of the matter from the assorting compartments when required. 15

The improvements consist partly in a means for supporting and separating the letters upon shelves in a casing and designating the spaces between the separating partitions; partly, in means for collecting 20 and holding the material in bulk before it is assorted; partly, in means for sustaining bags in a convenient position to receive the more bulky articles, or those of a certain class; partly, in the combination with the 25 side walls of a casing, of means for supporting a slatted flexible table so that the same can be moved in and out of the casing and partly, in a compartment-box hinged to a cross-bar in the casing, so as to be swung 30 up on such hinge, and having compartments or pigeon-holes open at the front, so that matter can be inserted in the front ends of the compartments while it is hanging within the casing, or turned upward to a horizontal 35 position. Such box is used when only a small amount of matter requires sorting. The casing of the cabinet is preferably made open at the back so that letters inserted from the front may be withdrawn 40 from the rear side, and operators may also insert or remove mail in the casing from opposite sides at the same time.

The invention will be understood by reference to the annexed drawing, in which— 45 Figure 1 is a front view of the cabinet composed of three casings; Fig. 2 is a cross section on line 2—2 in Fig. 1; Fig. 3 is a cross section on line 3—3 in Fig. 1, the view being drawn upon a larger scale than Fig. 50 1, and broken for want of room upon the drawing; Fig. 4 shows the upper right hand

corner of one of the casings upon the same enlarged scale; Fig. 5 is a horizontal section upon the same enlarged scale on line 5—5 in Fig. 2; Fig. 6 is an end view of a carrier-rod and sliding-block with part of a partition attached thereto; Fig. 7 is a plan of the same parts; and Fig. 8 is a front view of the same parts showing the journal upon one end of the carrier-rod. Fig. 9 shows 60 the label separate; Fig. 10 a modification of the label, and Fig. 11 shows a modification of the block *h*.

In Fig. 1, A, A' and A² designate three casings which may be made about thirty 70 inches wide, sixty inches high and ten inches deep, united by hinges *a*². The casing A' is shown with feet *a'* to rest directly upon the floor, but the casings A and A² are provided each with a handle *m* upon its outer edge 75 and with a roll *n* beneath its bottom to rest upon the floor, by which means the two outer casings of the cabinet can be drawn inwardly at any angle that may be desired to make them convenient of access to an 80 operator standing in front of a middle casing A'. The upper half of each casing is shown provided with shelves *B* extended between the sides *a* of the casing, and about midway of its height a slatted table-top *C* 85 is supported upon cleats or brackets *D*. In casing A, the bracket-cleats *D* are shown formed with notches *e* in which rods *b* may 90 rest to receive mail-bags *E* which are shown hung upon such rods in Fig. 1. 90

The brackets are shown in Fig. 2 pivoted upon the sides *a* of the casing by screws *d* and projected forward to support the slats *c* of the table-top *C*, before the casing. The table-top is shown in plan in Fig. 5 with a 95 handle *c'* upon its front edge to slide it upon the bracket-cleats *D*, and when slid inward it hangs down behind the brackets, in a pocket *c'', c''*, (see Fig. 3). The table-top may be removed from the brackets to 100 give access to the mail-bags *E* hung upon the rods *b*, and when neither the rods nor the table are required for use, the brackets may be turned upward upon the screws *d*, as shown by dotted lines *d'* in Fig. 2. In the 105 bottom of the casing A is shown a tub or drawer *F* provided with rolls upon the bottom and a jointed handle *F'* so that it may be removed from the casing and drawn from place to place upon the floor to receive and 110 collect the matter to be sorted in the cabinet, and to store the same until sorted. The

drawer F is merely indicated in Fig. 3. The shelves in the casing are adapted to furnish compartments of variable sizes for sorting matter of greater or less bulk, by employing 5 movable partitions *g* attached to blocks *h* constructed to slide upon a carrier-rod *i*. The rod has journals *j* (as shown on one end in Fig. 8), which journals are fitted to rotate in notches *k* formed in the front edges 10 of the sides *a*, and covered by bars *k'*, one of which is notched above each of the notches *k* to permit the removal of the rods by drawing one end forwardly and the other end longitudinally. The rotatability of the rod 15 permits all the partitions to be turned outwardly as indicated by the dotted lines *g'* in Fig. 3, so that when the matter has been sorted it may be more readily removed from the compartments between the partitions. 20 The front bottom corner of the block may be rounded, as indicated at *g* in Fig. 6, which permits the rotation of the partitions into the forward position shown at *g'* in Fig. 3; but the rear corner of the block or partition contacts with the shelf when the partitions are 25 thrown backwardly, thus holding them in their working position.

The shelves B, as shown in Fig. 3, are 30 preferably provided with one or more cleats or stops *r* set at varying distances from the front edge of the shelf and projected above the same at various heights, so that short letters set edgewise upon the shelf may contact with the first cleat, longer ones with the second by passing it over the first cleat, and so on. The cleats may be fitted adjustably to 35 grooves *r'*, *r''* in the sides *a*, so as to be set in any required positions. The rod *i* is prismatic in form (being shown square), so as 40 to turn with the blocks which are fitted movably thereto, and the front edges of the blocks are shown in Figs. 7 and 8 formed with guides *l* grooved to receive a removable label *o*. In this construction, the partition 45 is attached to the block by two screws and extends over one corner of the label, the partition-seat upon the block being recessed and the upper end of one of the corners notched so that the front corner of the partition 50 may fit over a notch *o'* in the corner of the label.

By removing one of the partition-screws marked *p* in Figs. 6 and 7, the front corner of the partition may be tipped upward to 55 permit the removal and changing of the label when desired. The label may be made as a cap *o''* covering the hole for the rod, in the block *h*, as shown in Fig. 10, thus enabling a partition to be applied to the rod 60 between others. The labels upon the blocks serve to designate the spaces at one side of each partition and thus indicate the location of the various sorts of articles in such spaces. Where it is not necessary to lock the label in

its place upon the block, the block may be 65 made with a dove-tailed slot or groove shown at *h'* in Fig. 10 and a tongue cut upon the lower corner of the partition and bent to fit the slot, as shown at *g''* in Fig. 11. The edges of the groove may be riveted down 70 upon the edges of the tongue, if desired to hold it therein permanently.

As the cabinet embraces three casings, which by means of the handles *m* and the rolls *n* can all be set equi-distant from the 75 operator, it is preferable that the provisions for accommodating the sorted matter should in the middle casing vary from those in the side casings, and I therefore prefer, below the shelves *b* in the middle casing in which 80 the compartments may be varied in size and arrangement by the movable partitions, to have a box *S* of pigeon-holes or compartments *S'* between such shelves and the tub in the bottom of the casing, with the upper 85 front edge of the box jointed by hinges *u* to a shelf or bar *t* extended across the casing for such purpose, and providing means to hold the box level or horizontal when in use. Such box is adapted for use in that position 90 when only a little matter is to be sorted. A back-board *v* is shown secured to the box to cover the rear ends of the pigeon-holes when the box is set horizontal, a brace *v'* serving to support it in such position, as most convenient for the operator, in sorting. Between the bar or shelf *t* which supports the box *S* and the table-top *o* shown in the casing *A'*, a set of drawers *w'* is shown in Figs. 1 and 3 adapted to hold a card-index. This 100 attachment adapts the entire device for special use as a filing-cabinet instead of a mere mail-sorting device.

The apparatus furnishes means in the 105 wheeled tub F for collecting the matter to be sorted, and its storage within the cabinet until sorted; means in the movable partitions *g* for forming compartments of variable size (where the relative quantity of the articles in the matter varies); means in the 110 bag E supported convenient to the operator to receive packages or any particular class of articles; means in the bracket-cleats D for supporting a movable table-top at a convenient height, to be drawn forward to support the matter when sorting, and pushed back into the casing of the cabinet, or projected from its opposite side for use thereat; means in the box *S* having pigeon-holes 115 *S'* for sorting small quantities of articles and holding the box either horizontal or vertical while sorting; and finally, means in the drawers *w* for sustaining a card-index in connection with the cabinet for reference to the contents of the pigeon-holes. It is well 120 known that matter can be sorted most rapidly when the series of compartments open upon the same level, as in the mail-bags E;

and the box S is therefore preferably set in a horizontal position when in use, and thrown backward into the casing when not required for use.

5 The cabinet, as shown, furnishes large facilities for filing with adjustable compartments and labels upon the same when desired. As the most important feature of the invention is the adjustability and rotatability of the partitions upon the shelves and the facility of removing the rod with all the partitions from any shelf, it is evident that this feature may be used without employing all the other features of the invention.

10 Where parties have a cabinet which is lacking in such adjustable partitions, a case may be made resembling the upper half of one of the cases shown herein, which may be hinged to such cabinet to enlarge its classifying capacity. By having the compartments open at the front and back, as shown in the drawing, the matter may be placed in the compartments from one side and removed from the opposite side; and the

15 cleats r at the edges of the shelves may be omitted in such case if desired. If preferred, means may be provided in the form of a movable skeleton frame, to obstruct the rear sides of the compartments while filling them from the front, and capable of sliding

20 into coincidence with the shelves, where it is desired to remove the matter from the back of the compartments. If the improvements are used in a mere filing cabinet, it would be

25 provided with doors to exclude the dust.

The most essential features of my invention are partitions made movable upon a rod so as to be adjustable lengthwise thereon, and removable when desired with the rod, and the cleats or raised projections at the rear edge of the shelf for setting matter of different lengths flush with the front ends of the compartments. The operator can readily tell when sorting letters in such compartments, whether they should contact with the first or second obstruction upon the back of the shelf, and would acquire the habit of raising them at a suitable distance to contact with the proper obstruction and hold them even with the front of the casing. This greatly facilitates the removal of the papers or letters from the compartments when sorted.

Having thus set forth the nature of the invention what is claimed herein is:

1. In a classifying cabinet, the combination, with a casing, of horizontal shelves fitted therein, partitions dividing the space upon the shelves, and a series of adjustable cleats projected upwardly from the shelf at varying heights to stop letters of various

lengths when inserted between the partitions.

2. In a classifying cabinet, the combination, with an upright casing, of a series of shelves arranged closely one above another to support mail matter thereon, a rod extended rotatably over the front portion of each shelf, a series of blocks fitted adjustably upon each rod with a partition attached to each block and the partitions rotatable with the rod between the shelves and proportioned to clear the under sides of the shelves when rotated outwardly therefrom.

3. In a classifying cabinet, the combination, with an upright casing, of means in the upper part for classifying papers, and having a space below the same with rods fitted removably between the sides of the casing at the top of such space and adapted to receive and support bags, by sliding upon the said rods, for receiving letters or papers.

4. In a classifying cabinet, the combination, with an upright casing having means in the bottom for receiving letters and papers in bulk, of brackets upon the inner sides of the casing above the said letter-receiving means and projecting outward from either side of the casing, and a slatted flexible table or disk-top supported movably upon the brackets and adapted to slide in and out of the casing upon the brackets.

5. In a classifying cabinet, the combination, with an upright casing having means in the bottom for receiving letters and papers in bulk, of bracket-bars pivoted upon the inner sides of the casing above the said letter-receiving means and projecting outward from the front side thereof, and a slatted flexible table-top adapted to slide in and out of the casing upon the said brackets.

6. In a classifying cabinet, the combination, with an upright casing, of brackets arranged upon the inner side of the same at a suitable height, a slatted flexible table-top movable into and out of the casing upon the said brackets, a cross-piece extended rigidly between the sides of the casing below the said table-top and a rectangular frame hinged to the front edge of such cross-piece and having a series of compartments open upon the front and back sides and adapted to be turned horizontally at the front of the casing, for access more freely to the compartments.

In testimony whereof I have hereunto set my hand in the presence of two subscribing witnesses.

CARLISLE H. MIDDAUGH.
